Atty.

UNITED STATES PATENT OFFICE.

FRANK A. HALLECK, OF OAK PARK, ILLINOIS, ASSIGNOR TO SULLIVAN MACHINERY COMPANY, A CORPORATION OF MASSACHUSETTS.

FORGING MACHINE.

1,405,116.

Specification of Letters Patent. Patented Jan. 31, 1922.

Application filed March 20, 1917. Serial No. 156,192.

To all whom it may concern:

Be it known that I, FRANK A. HALLECK, a citizen of the United States, residing at Oak Park, in the county of Cook and State 5 of Illinois, have invented certain new and useful Improvements in Forging Machines, of which the following is a full, clear, and exact specification.

My invention relates to forging machines.

10 It has for its object to guide and control one of the forging members of such a machine in an improved manner. A more specific object of my invention is to provide an improved guiding means for the upsetting 15 dolly of a forging machine whereby the dolly is guided in its movement in such a manner that excessive vibration and breakage of the parts is prevented. A still further object of my invention is to provide 20 improved guiding means of the character set forth, adapted to be readily controlled, the same preferably being movable to and from operative position with the work clamping means.

25 In the accompanying drawings, I have shown for purposes of illustration one embodiment which my invention may assume in practice, illustrating the same as applied to a forging machine or drill sharpener of the 30 Wineman type.

In these drawings,

Fig. 1 is a partial longitudinal sectional view of a forging machine equipped with my improvement.

35 Fig. 2 is a partial sectional view taken on line 2—2 of Fig. 1, showing the dolly guiding means in end elevation and attached to the machine.

40 Fig. 3 is a detail central sectional view of the dolly guiding means per se.

Fig. 4 is a detail view showing the same in end elevation.

In these drawings, I have illustrated a sharpener comprising a frame 1 having a 45 stationary clamping die 2 and a vertically movable clamping die 3, the latter being operated through the medium of a movable crosshead 4, which is in turn operated by a piston 5 through toggle mechanism 6. Co- 50 operating with these clamping dies 2 and 3, and acting upon the end of a drill steel clamped between the same, is a reciprocating upsetting dolly 7 slidably mounted upon the frame 1 and slidably connected, as at 8, 55 to the end of a striking pin 9, which is in

turn operated by a piston 10 of a horizontally disposed motor 11.

In my improvement, this dolly 7 is guided in its movement by a floating or yielding guide member or plate 12 which is normally 60 pressed into engagement with the dolly by resilient means. These means, as shown, comprise a plurality of coiled springs 13, preferably disposed in suitable recesses or cavities 14 in a guide carrying member 15 65 suitably attached at 16 to the crosshead carrying the upper or vertically movable clamping die 3. In a preferred form, these springs 13 are disposed along the center line of the plate 12 in such a manner as to hold 70 the same against the dolly with an even pressure, and the plate 12 is permitted a limited vertical movement, the same moving in a recess 17 in the member 15. It will also be noted that in the construction shown, the 75 lower side edges of the floating plate 12 engage with suitable cooperating flanges 19 on the member 15 in such a manner as to limit the possible downward movement of the plate 12 and prevent the same from dropping 80 out of place. Here, attention should also be directed to the fact that surfaces 20 are provided upon the member 15 beneath the plate 12, and herein at right angles thereto, which may engage with the sides of 85 the dolly and prevent excessive lateral movement thereof, and that corresponding surfaces 21 may be provided upon a cooperating lower plate 22 disposed beneath the dolly and between the latter and the frame 1. 90

In the operation of the machine, it will be noted that through the action of the plate and the additional guiding surfaces provided, excessive vibration and the resultant breakage of the parts is prevented, at the 95 same time that the plate is adapted to use with dollies of different sizes and to take up wear between the various surfaces. It will also be noted that due to the fact that the member 15 is attached to a part moving 100 with the crosshead 4, this member 15 and the guide 12 will be automatically lifted out of engagement with the dolly 7 to permit access to be had thereto when the clamping die 3 is lifted to release the steel, the plate 105 12 then being held by the springs 13 in the position shown in Fig. 4, with its lower side edges in engagement with the flanges 19 on the member 15. Obviously, when the parts are in this position, not only may the steel 110

be removed, but the dolly may be removed or changed when desired by simply slipping the same off the end of its actuating or striking pin 9.

5 While I have in this application specifically described one embodiment which my invention may assume in practice, it is of course to be understood that the invention may be modified and embodied in various 10 other forms without departing from its spirit, it being my intention to include all such modifications within the scope of the appended claims.

What I claim as new and desire to secure 15 by Letters Patent is:

1. In a forging machine, work clamping means, a dolly, a hammer operating upon said dolly, and means for resiliently guiding said dolly.

20 2. In a forging machine, work holding means, a dolly, a hammer adapted to operate upon said dolly, and guiding means resiliently engaging said dolly during operation thereof, but movable out of engagement therewith at intervening periods to 25 permit access thereto.

3. In a forging machine, work clamping means, a dolly, a hammer operating upon said dolly, a member for guiding said dolly, 30 and a spring for normally pressing said member into operative position for guiding said dolly during operation thereof.

4. In a forging machine, work clamping means, a dolly, a hammer operating upon 35 said dolly, and guiding means for said dolly resiliently engaging the latter during dollying operation, the operative engagement of said guiding means with said dolly being controlled by said clamping means.

40 5. In a forging machine, clamping means including a movable clamping member, a dolly acting upon work clamped between said clamping means, and normally operative dolly vibration absorbing means movable with said movable member.

6. In a forging machine, clamping means including a movable clamping member, a dolly acting upon work clamped between said clamping means, and normally operative resilient dolly vibration absorbing and guiding means movable with said movable member.

7. In a forging machine, work clamping means, a work engaging dolly, a hammer 55 operating upon said dolly, and a spring pressed member carried by said clamping means and normally engaging with said dolly during the operation thereof.

8. In a forging machine, work clamping 60 means, a dolly, a hammer operating upon said dolly, and dolly guiding means disposed on opposite sides of said dolly including a fixed member and a spring pressed member normally engaging said dolly.

65 9. In a forging machine, clamping means

including a movable element, a dolly, a hammer operating upon said dolly, and dolly guiding means disposed on opposite sides of said dolly including a spring pressed plate normally engaging said dolly and 70 bodily movable with the movable element of said clamping means.

10. In a forging machine, cooperating clamping elements, a dolly engageable with the work clamped between said elements, a 75 guiding member relative to which said dolly is movable, and resilient means acting along the median line of said member normally pressing the same into engagement with said dolly.

11. In a forging machine, cooperating clamping elements, a dolly engageable with the work clamped between said elements, a guiding member engageable with said dolly, and a plurality of coiled springs acting 85 along the median line of said member normally pressing the same into engagement with said dolly.

12. In a forging machine, cooperating clamping elements, a dolly engageable with the work clamped between said elements, a guiding member engageable with said dolly, resilient means normally pressing said guiding member into engagement with said dolly, and means for limiting the movement 95 of said guiding member.

13. In a forging machine, clamping means including a movable clamping member, a dolly engageable with the work clamped in said clamping means, a guiding member disposed at one side of said dolly, cooperating guiding means disposed on the other side of said dolly, resilient means normally pressing said member into engagement with said dolly, and a reciprocating member intermittently engageable with said dolly.

14. In a forging machine, cooperating clamping elements, a dolly engageable with the work clamped between said elements, a guiding member engageable with said dolly, resilient means normally pressing said guiding member into engagement with said dolly, and cooperating means disposed on opposite sides of said dolly for limiting the lateral movement thereof.

15. In a forging machine, cooperating clamping elements, a dolly engageable with the work clamped between said elements, a guiding member engageable with said dolly, resilient means normally pressing said guiding member into engagement with said dolly, and cooperating means disposed on opposite sides of said dolly and above and below the same for limiting the lateral movement thereof.

16. In a forging machine, work clamping means, a dolly acting upon work held by said clamping means, and yielding means engaging said dolly for guiding the same.

17. In a forging machine, work clamping

means, a dolly acting upon work held by said clamping means, and a floating member engaging said dolly for guiding the same.

18. In a forging machine, work clamping means including a movable clamping member, a dolly acting upon work held by said clamping means, and means for guiding said dolly including a member carried by and movable with said movable clamping member.

19. In a forging machine, work clamping means including a movable clamping member, a dolly acting upon work held by said clamping means, and means for guiding said dolly including a yielding dolly engaging member carried by and movable with said movable clamping member.

20. In a forging machine, work clamping means comprising a fixed clamping member and a cooperating movable clamping member, a dolly acting upon work held by said clamping means, and means for guiding said dolly including a fixed guiding member and a cooperating guiding member carried by and movable with said movable clamping member.

21. In a forging machine, work clamping means comprising a fixed clamping member and a cooperating movable clamping member, a dolly acting upon work held by said clamping means, and means for guiding said dolly including a fixed guiding member and a cooperating dolly engaging member yieldingly mounted on and movable with said movable clamping member.

22. In a forging machine, a work clamping means including a clamping member movable into a plurality of positions, a dolly, a member adapted to guide the dolly, and a member controlled by the position of said first named member for placing said dolly guiding member under pressure when said clamping member is in work clamping position.

23. In a forging machine, a work clamping means including a clamping member movable into a plurality of positions, a dolly, a member adapted to guide the dolly, and resilient means controlled by the position of said first named member for placing said dolly guiding member under pressure when

said clamping member is in work clamping position.

24. In a forging machine, a work clamping means including a movable clamping member, a dolly, a member adapted to be moved into engagement with said dolly to hold it in operating position, and a member movable to place said dolly engaging member under pressure when said clamping member is in work clamping position.

25. In a forging machine, clamping means including a movable clamping member, a dolly adapted to act upon work clamped between said clamping means, guiding means including a member engageable with said dolly, a spring carried by said clamping means and adapted to press said guiding member against said dolly, said parts being constructed and arranged so that movement of the movable clamping member to clamping position places said spring under compression.

26. In a forging machine, clamping means comprising a movable member, a dolly adapted to operate upon the work clamped by said clamping means, guiding means including a member engageable with said dolly and movable out of engagement therewith to permit access to said dolly when said movable clamping member is moved to non-clamping position, a spring carried by said movable member and adapted when said movable clamping member is in clamping position to press said dolly guiding member against said dolly.

27. In a drill sharpener, the combination comprising a dolly, a base, a dolly guide on said base having bottom and side walls formed thereon, a cover member adapted to cooperate with said guide in the holding of said dolly, and resilient means for holding said cover member in operative relation to said dolly.

28. In a forging machine, clamping mechanism comprising a movable jaw, a dolly, a dolly holder having a movable section, and means carried by said movable jaw and engaging said section for retaining the latter in operative relation to said dolly.

In testimony whereof I affix my signature.

FRANK A. HALLECK.
